John M. Deamer

UNITED STATES PATENT OFFICE.

OTTO S. GROPPER, OF LONG ISLAND CITY, NEW YORK.

COMBINED LICENSE PLATE AND TAIL LIGHT.

Application filed April 17, 1922. Serial No. 554,146.

To all whom it may concern:

Be it known that I, OTTO S. GROPPER, citizen of the United States, and resident of Long Island City, New York, in the county 5 of Queens and State of New York, have invented certain new and useful Improvements in Combined License Plates and Tail Lights, of which the following is a specification.

The present invention relates to license-10 plates for automobiles, having reference particularly to an improved combination license-plate and tail light.

The invention has for an object the provision of a device of this character which is 15 equally adaptable for daylight and night use.

Further objects of the invention being to provide a housing structure having means for coincidentally illuminating a tail light 20 lens and a removable and interchangeable, perforated license plate adapted to be held in fixed relation without liability of rattling, but which may be readily removed by an authorized person.

Another object of the invention being the provision of means for preventing unauthorized persons from removing the plate.

In the attainment of these and other objects, I provide a housing having an open 30 front, and a perforated license plate, and means for detachably fastening said license-plate, said housing having a communicating compartment open in front and provided with a fixed lens, means for lighting the interior of the housing whereby the license-plate and tail-light lens may be coincidentally illuminated, means for locking the license-plate, and other novel features all as hereinafter fully described and specifically set forth in the appended claims.

In the accompanying drawings forming part of this specification, Figure 1 is a front elevation illustrating an embodiment of my improvement;

Fig. 2 is an end view thereof showing the elements of the invention in locked relation;

Fig. 3 is a fragmentary sectional view taken on the line 3—3 of Fig. 2;

Fig. 4 is an end view showing the device 50 unlocked for removal of the license-plate;

Fig. 5 is a cross sectional view taken on the line 5—5 of Fig. 1; and

Fig. 6 is a cross section taken on the line 6—6 of Fig. 1.

In the drawings, 1 indicates a hollow hous-

ing comprising a rectilinear compartment 2 and a domed communicating compartment 3, having an open front comprising a cylindrical extension 4 within which is fixed a colored lens 5. Lamps 6, preferably electric 60 lamps, are mounted on the bottom wall of the housing 1, and extend into the compartment 2, whereby the compartments 2 and 3 are coincidentally illuminated to allow of light rays passing through the lens 5 and 65 the removable license plate which comprises a metal sheet 7, perforated with suitable indicia 8, and a plate 9 of opalescent glass, the metal sheet 7 having flanges 7^a which are bent over the edges of the plate 9, whereby 70 the glass is securely held on the inner surface of the sheet 7.

The front wall of the housing 1 is provided with a rectilinear opening 10 which is surrounded on three sides by means of 75 flanges 11, 12; and the forward edge of one end wall 13 of the housing 1 is spaced from the face of the housing sufficiently to admit of inserting the license-plate, flanges 11^a being provided for holding said license-plate 80 against inward lateral movement. To prevent rattling of the license-plate suitable springs 14 are mounted between the flanges 11 and 11^a, as shown in Fig. 1 of the drawings. The housing 1 is further provided 85 with sockets 15 and 16 adapted for engaging suitable brackets, whereby the device may be fixed to an automobile.

As a means for opening and closing the inlet to the housing, I provide a sliding door 90 17, said door being mounted on studs 18 which extend outwardly from the end wall 13 and pass through parallel slots 19 of the door 17, said slots extending at an angle to the plane of the face of the housing, where- 95 by the door has a normal tendency to close by gravity when it is positioned as shown in Fig. 4 of the drawings.

Fixed to a rotatable stud 20 which is mounted on the end wall 13 is a crank-arm 100 21 having a pin 22 extending inwardly through a segmental slot 23 of the wall 13.

The door 17 is provided with a segmental recess 17^a on its rearward edge adapted to allow for swinging movement of the pin 105 22 in the arc of a circle described by the slot 23. The crank-arm 21 is normally maintained in position shown in Fig. 2 of the drawings, by means of a spring 24, having one end fixed to the end wall of the 110

housing and the other end in bearing relation with the crank arm 21, whereby when the door 17 is closed said crank arm automatically swings downwardly.

5 The device is further provisioned with an interiorly fixed lock 25, of any adaptable variety, having a bolt 26 which engages over the pin 22 when the crank arm 21 is thrown downwardly, as shown in Fig. 2 of 10 the drawings, a key-hole 27 being extended through the wall 13, whereby a key may be inserted into the lock for sliding the bolt 26 out of engagement with the pin 22 when it is desired to open the door 17.

15 The metal sheet 7 of the license plate is painted a color very much darker than and sharply contrasting with the color of the glass plate 9 whereby the indicia is distinctly visible in daylight, and the relatively light color of the plate 9 admits of light rays being projected through the 20 indicia at night.

It is manifest that by employing my improved device the license-plate while readily 25 removable and interchangeable, is thoroughly protected against removal without the aid of a proper key, thus entirely obviating liability of having it unlawfully removed.

While I have illustrated and described 30 a fair example of my invention, I do not wish to be understood as confining myself to the specific details shown, as under the spirit of my invention I believe that I am entitled to employ such variations of detail 35 as may fall within the scope of the appended claims.

Having thus described my invention, what

I claim as new and desire to secure by Letters Patent, is:

1. In a means for closing a casing having an end inlet and a segmental slot, a sliding door having an edge recess, and a spring-actuated crank arm having a pin which extends through said slot of the casing, and an interiorly located lock having a bolt for engaging over said pin to prevent turning of the crank arm. 40

2. In a means for closing a casing having an end inlet and a segmental slot, a sliding door having an edge recess, and means for mounting said door whereby it may coincidentally slide rearwardly, and upwardly away from the casing recess, and a spring-actuated crank arm having a pin which extends through said slot of the casing, and an interiorly located lock having a bolt for engaging over said pin to prevent turning of the crank arm. 50

3. In a means for closing a casing having an end inlet and a segmental slot, a sliding door having parallel slots extending upwardly and obliquely from the plane of the front edge of the door and a recess in its back edge, and studs for mounting said door, and a spring-actuated crank arm having a pin which extends through said slot of the casing, and an interiorly located lock having a bolt for engaging over said pin to prevent turning of the crank arm. 60

Signed at New York, in the county of 70 New York and State of New York, this 15th day of April, A. D. 1922.

OTTO S. GROPPER.
